UNITED STATES PATENT OFFICE.

NEWELL E. TAYLOR, OF BROOKLYN, NEW YORK, ASSIGNOR TO INGERSOLL-RAND COMPANY, OF JERSEY CITY, NEW JERSEY, A CORPORATION OF NEW JERSEY.

SURFACE CONDENSER.

Application filed August 14, 1925. Serial No. 50,197.

This invention relates to steam condensers and with respect to its more specific features to means for increasing the efficiency of steam condensers by distributing the 5 steam throughout the length of the condenser in proportion to the specific steam condensing capacity of the cooling surfaces.

The invention has for its object to enable steam to be led in an efficient manner to the cooling surfaces in proportionate amounts corresponding to the specific steam condensing capacity of the cooling surfaces.

Other objects and advantages of the invention will be in part obvious and in part 15 pointed out hereinafter.

In the drawing forming part of the specification and in which similar reference characters refer to similar parts—

Figure 1 is a horizontal longitudinal section taken along the line 1—1 looking in the direction of the arrows, of a condenser constructed in accordance with the practice of the invention.

Figure 2 is a cross section of the condenser 20 taken along the line 2—2 looking in the direction of the arrows, and

Figure 3 is a cross section of the condenser taken along the line 3—3 looking in the direction of the arrows.

The condenser is provided with a steam inlet A, an outlet B for condensate, and an outlet C leading from a devaporizer D of any suitable construction for attachment to a vacuum pump (not shown). Steam entering at the inlet A is adapted to contact with cooling tubes E arranged transversely to the direction of flow of steam entering to be condensed thereby. The tubes E are supported at their ends in tube sheets F and 35 are supplied with water from an inlet head G at one end and discharge their water into a discharge head H.

It is understood that as the steam contacts with the tubes E, the water therein 45 becomes heated before passing to the discharge head H. The temperature of the water in the tubes E will therefore increase as the distance from the inlet head G increases resulting in varying and progressively increasing temperatures along the 50 length of the tubes E in the direction of the flow of cooling water therewithin. This condition causes that portion of the condenser near the inlet head G to have greater 55 steam condensing capacity than portions

more remote from the inlet head G since the specific steam condensing capacity of tube surface decreases in the direction of the warm ends of the tubes. Therefore, as the steam condensing capacity decreases, the 60 steam flowing around the tubes E must penetrate more deeply into the banks of tubes before complete condensation of the steam takes place. For this reason penetration of the steam in the usual condenser is much 65 less at the cool tube ends than at the warm tube ends.

By this invention, means is provided to convey more steam to the cooler end of the condenser than to the warm end, and 70 in intermediate portions in quantities proportionate to their specific steam condensing capacity. To this end the outer casing J is formed larger near the cool ends of the tubes E than at the warmer ends of the 75 tubes to form steam lanes or by-passes around and outside the upper levels of the tubes E to the lower banks of the tubes E. Preferably the casing J is tapered so that the steam lanes K taper from a maximum at 80 the cool end of the casing and graduate to substantially nothing at the warm end of the casing. The amount of steam by-passed about the upper banks of cooling tubes therefore decreases in quantity as the distance decreases from the cool ends of the tubes E.

It will be noted that an increase in efficiency will be produced by this arrangement in that the steam by-passed to the lower section of the condenser encounters less 90 resistance, or in other words there is less pressure drop than results if the steam is passed through the narrow passages between the tubes E. In order to operate the condenser efficiently every portion of each tube 95 should contact with steam at a temperature substantially like that existing at the steam inlet and in the usual condenser to have the relatively large quantity of steam commensurate with the condensing capacity of the 100 cool end of the condenser forced through the closely spaced tubes E, the pressure drop is a substantial factor because of the high velocity required to pass the relatively large amount of steam through the small openings provided and the consequent lowering of the steam temperature. At the warmer end of the condenser the pressure drop is not so great, for the reason that only a relatively 105 small quantity of steam can be condensed 110

at the warm end and the steam velocity is therefore materially lower than at the cold end. This invention therefore tends to equalize the pressure drop or friction head throughout the length of the condenser.

I claim:

1. A surface condenser comprising an inlet for steam to be condensed, a condensate outlet and an outlet for air and uncondensable gases, a plurality of parallel tubes transverse to the direction of steam flow for conducting cooling water and having decreasing specific steam condensing capacity in the direction of water flow therethrough, and a casing about said tubes forming a steam lane to conduct greater quantities of steam directly to lower tube levels at the cold ends of the tubes than at the warm ends.
2. A surface condenser comprising an inlet for steam to be condensed, a condensate outlet and an outlet for air and uncondensable gases, a plurality of parallel tubes transverse to the direction of steam flow for

conducting cooling water and having decreasing specific steam condensing capacity in the direction of water flow therethrough, and a tapered casing about the tubes forming a by-pass for steam to lower tube levels graduated in size from the cool end of the cooling tubes to a minimum at the warm ends of the tubes.

3. A surface condenser comprising an inlet for steam to be condensed, a condensate outlet and an outlet for air and uncondensable gases, a plurality of parallel tubes transverse to the direction of steam flow for conducting cooling water and having decreasing specific steam condensing capacity in the direction of water flow therethrough, and a casing about said tubes forming a larger steam lane at the cool end of the tubes than at the warmer end thereof to conduct steam directly to lower tube levels.

In testimony whereof I have signed this specification.

NEWELL E. TAYLOR.
